SHOE PRESSING MACHINE

Roy F. McClenathan, Erie, Pa., assignor to Lamac
Process Company, Erie, Pa., a corporation

Application May 26, 1932, Serial No. 613,737

12 Claims. (Cl. 12—33)

In the present invention I provide a machine to facilitate securement of a shoe sole to its upper, where a cementitious agent is used as a securing medium, an object of the invention being to embody in the machine articulate mechanism, the digits of which automatically move under pressure on the shoe to exert a constant and substantially uniform pressure on all parts of the sole, regardless of its shape or size and the conformation of the shoe.

Preferably in the present invention I embody a series of units, each unit being adapted for the reception of a pair of shoes and the entire series joined together as an entity, permitting several pairs of shoes to be supported and retained by the machine simultaneously during the period that the soles are being secured.

Other objects of the present invention will be apparent from the following description of the present preferred form thereof taken in connection with the accompanying drawings, wherein

Fig. 1 is an elevational view of a pressing machine constructed in accordance with the present invention, one of the units thereof illustrating the application of the invention;

Fig. 2 is a fragmentary vertical, sectional view taken through one of the units, illustrating the application of the machine to a shoe;

Fig. 3 is a detail fragmentary top plan view of the base of one of the units, showing one of the articulate plates associated with the unit;

Fig. 4 is a detail fragmentary transverse, sectional view taken on the line 4—4 of Fig. 2;

Fig. 5 is a detail side elevational view of one of the shoe pressers forming a part of the present invention;

Fig. 6 is a top plan view thereof; and

Fig. 7 is a detail fragmentary perspective view of one of the articulate plates.

The machine of the present invention, as an entity, consists of a supporting frame 8, which has a block 9 revolvably mounted therein and adapted to be held in any predetermined position through the medium of a locking pin 10 which is engageable in any one of a series of recesses 11, formed in the side of the block. The block in the present instance, is shown to be of polygonal configuration in cross-section to provide a series of flat surfaces, each of which is adapted for the reception of a pressing unit generally designated 12.

Each of the pressing units consists of a base 13, provided with ears 14, through which securing means are engageable for connecting the base to the block 9. The base is divided into

twin compartments, each of which, designated 15, is substantially of the shape of a shoe sole. Ribs 16, 17 and 18 form the bottom of the base 13 and project appreciably beyond the bottom of the compartments 15 proper. The ribs 17 and 18 likewise serve to support the superstructure of the base hereinafter described. Upon reference to Fig. 3 of the drawings, it will be noted that each of the ribs 18 is provided with a pair of longitudinally extending recesses 19 so arranged that one recess will be within the confines of the sides of each of the compartments 15. It will be noted, also, upon reference to Fig. 3 of the drawings, that the closed end of each of the compartments 15 is provided with a web 20 formed to provide a toe supporting portion for the base superstructure. The ends of the base are equipped with bosses 21 provided with screw threaded openings for a purpose more fully hereinafter set out.

A superstructure is carried by each compartment 15 of the base 13, consisting of an articulate plate 22, a pad 23 and a presser foot 24. The articulate plate 22 consists of two digits or parts, the body or sole portion of which, designated 25, is centrally cupped or dished, while the tail or heel portion 26 is likewise centrally cupped or curved. The tail or heel portion 26 is provided with a biled extension 27 which is hooked over a complementary pintle or rod 28, formed on the bottom of the sole portion 25 of the plate. As appears from the drawings, ample space is provided between the sole and heel portions of the plate to provide freedom of movement of the digits or parts thereof, the adjacent terminals of said digits being preferably bevelled or tapered to insure free relative side movement. The tail or heel portion 26 of the plate is provided with a transverse rib 29, adapted to be mounted in a recess 19. The rib 29 is rounded to permit free rocking movement of the tail or heel portion of the plate on its supporting rib 18. It will be noted that when the articulate plate is in position in one of the compartments 15, the sole portion 25 thereof is normally supported by the toe piece 20 of the base, above rib 17, and has superimposed thereon the pad 23. The pad 23 in the present instance consists of a rubber cushion, the top of which is shaped to generally conform to a shoe sole and arch. In practice, the shoe is mounted on the pad or cushion 23, preferably in the manner shown in Figs. 2 and 4 of the drawings.

The shoe presser forming a part of each unit comprises a last, the body portion 30 of which is

detachably engaged to an articulate base generally designated 31. The front portion of the base is detachably engaged to the body 30 by suitable means 32 and is shaped to conform to the configuration of a shoe. The rear portion of the base has one terminal thereof enlarged and bifurcated to provide a pair of segmental plates, one of which, designated 33, is provided with teeth 34, while the other plate, designated 35, is equipped with an abutment lug 36. The forward ends of the plates 33 and 35 unite and are recessed to receive a bar 31, circular in cross-section, which is formed on the rear terminal of the front part of the articulate base 31. The body portion of the last 30 has a pawl 38 fixedly mounted on one side thereof which is adapted to coact with the teeth 34. The opposite side of the body portion 30 of the last is provided with a finger 39 arranged in the path of movement of the abutment lug 36. The fastening means 32 may be adjusted to permit relative movement of the rear part of the base 31. When the desired angularity is obtained, pressure causes the pawl 38 to be locked into engagement with the teeth 34, as shown in Fig. 5 of the drawings. Downward movement of the rear portion of the base 31 is limited by reason of the abutment lug 36 and finger 39. The top of the body portion 30 of the last is provided with a recess 40 which is adapted for the reception of the lower terminal of a clamping screw 41.

It will be noted from the drawings that one of the clamping screws 41 overhangs each of the compartments 15 of the base 13 and for the purpose of supporting the screws, I provide a bearing bar 42 for each unit. The bearing bar is carried by the unit base 13 through the medium of shafts or rods 43, the ends of which are screw threaded. The inner ends of the shafts or rods 40 are engaged with the bosses 21, while the outer ends engage the bearing bar 42. For the purpose of feeding the screws 41, I provide, in the present instance a hand wheel 44.

In using this device, it is apparent that an articulate plate 22 is mounted in each of the compartments 15 and the pad or cushion 23 then mounted thereon. The shoe, indicated in the drawings at S, is superimposed on the pad, as illustrated to advantage in Fig. 2, after which the shoe presser or last is inserted in the shoe. It is of course, understood that before placing the shoe on the pad or cushion, the shoe sole is engaged to the shoe upper through the medium of a cementitious agent and the sole properly positioned on the upper. The articulate base 31 of the last is then adjusted in order to position said base in substantial contiguity with the insole of the shoe throughout the length of the base, adjustment of said base being accomplished in a manner already described. The feed screw is then fed against the body portion 30 of the last through rotation of the wheel 44, thereby flexing the shoe into the pad 23. This pressure is transferred to the articulate plate 22, urging the proximate ends of its digits or parts upwardly and correspondingly exerting pressure on the pad or cushion 23 and urging the latter against all parts of the sole without danger of slippage of the latter. Each unit is adapted for the reception of one pair of shoes and all of the feed screws 41 may be successively operated by the same removable wheel 44. After the various units of the pressing machine have been filled, the shoes are permitted to stand for a predetermined time until positive adherence of the sole with the shoe upper is ef-

fected, after which the shoes are removed from the units in a manifest manner.

It is of course, understood that although I have shown the units as being associated with the block 9 in order to provide a multi-unit machine, the units are also used individually and when so used, the supporting ribs 16, 17 and 18 provide a substantial foundation for the unit. The units therefore, may be used either singly or in multiple without any change whatsoever in the structures thereof.

It is to be understood that the pad or cushion 23 is preferably made of solid rubber, which however, has sufficient resiliency to return to normal shape after having been distorted for several hours under the pressure of the shoe last. It is further to be understood that the digits or parts of the articulate plate 22 have the proximate ends thereof sufficiently spaced to permit freedom for vertical, as well as slight lateral relative movement to insure positive engagement of the pad or cushion 23 with all parts of the sole. Manifestly, various sizes of shoe lasts may be used to assure effective operation of the unit with various sizes of shoes.

Although I have herein described the present preferred form of my invention, it is nevertheless to be understood that various changes may be made in the construction, proportion and arrangement of parts, within the scope of the claims appended hereto.

What is claimed is:

1. A unit for use in pressing a shoe sole against its upper during a repair operation including a base equipped with an articulate plate, a yieldable shoe supporting pad superimposed on the plate, and articulated means engageable in the shoe and movable inwardly against the sole of the latter to automatically urge the parts of the articulate plate against the pad.

2. A unit for uniting a shoe sole to its upper, including a base equipped with a pad-carrying, shoe supporting plate, and a last for engagement in the shoe, said plate and last each being articulated to flex the pad against the shoe sole in response to pressure on said last.

3. A unit for uniting a shoe sole to its upper, including a base equipped with a pad-carrying, shoe-supporting plate, a last for engagement in the shoe, said plate and last each being articulated, and means carried by the base and engaged with the last for operating the latter and correspondingly operating said plate.

4. A unit for use in uniting a shoe sole to its upper comprising an articulated pad-carrying, shoe-supporting plate, a last for engagement in the shoe including a movable sole-engaging part, means on the last to hold said movable part in a fixed position in a shoe, and means to relatively move said last and plate for flexing the pad against the shoe sole.

5. In a sole pressing member for a shoe press, a frame including a vertical plate configured to receive the front portion of a shoe and a flange projecting inwardly of said frame at the front thereof, a sole plate supported at one end by said flange, a shank plate pivoted intermediate its ends to said frame and engaging said sole plate, and a flexible pad mounted on said plates, said pad flexing to conform to the contour of the sole and shank of a shoe pressed thereagainst and shifting said plates to a relatively angular position to accommodate said flexing.

6. In a sole pressing member for a shoe press, a frame, a pair of cooperating plates shiftably

- carried by said frame, said plates being disposed in interengaging relation, and a flexible pad supported by said plates and shifting said plates to a relatively angular position upon the application of pressure thereto by a shoe, the shifting of said plates accommodating the flexing of said pad to conform with the contour of the shoe.
7. In a sole pressing member for a shoe press, a frame, a sole plate shiftably supported at the front of said frame, and a shank plate shiftably carried by said frame and engaging said sole plate, said plates being shifted to a relatively angular position upon application of pressure thereto by a shoe to conform with the contour of the shank and sole of said shoe.
8. In a sole pressing member for a shoe press, a frame, and a pair of interengaging cooperating plates shiftably carried by said frame, said plates being shifted to a relatively angular position to conform to the contour of the sole and shank of a shoe pressed thereagainst.
9. In combination, a plate shaped to form a sole last, a handle projecting upwardly from said sole last, a second plate shaped to form a shank last and movably connected to said sole last, a flange carried by said shank last, and means engaging said flange to hold said shank last in a selected position relative to said sole last.
10. In combination, a plate shaped to form a sole last, a handle projecting upwardly from said sole last, a second plate hinged to said sole last and shaped to form a shank last, a flange carried by said shank last and positioned adjacent said handle, and means cooperating with said flange to selectively hold said shank last relative to said sole last.
11. In combination, a plate shaped to form a sole last, a handle projecting upwardly from said sole last, a second plate shaped to form a shank last hinged to said sole last, and means to selectively lock said shank last relative to said sole last.
12. A machine for uniting a shoe sole to its upper including a plate adapted to form a sole last, a second plate shaped to form a shank last and movably connected to the sole last, and means supported by said lasts for effecting selective locking of one of said lasts relative to the other.

ROY F. McCLENATHAN. 25
